FUSE BLOCK AND LIGHTNING ARRESTERS

Filed April 13, 1928

WITNESS: J. T. L. Wright

ATTORNEY

UNITED STATES PATENT OFFICE.

HERBERT A. TAYLOR, OF WILMINGTON, NORTH CAROLINA.

FUSE BLOCK AND LIGHTNING ARRESTER.

Application filed April 13, 1928. Serial No. 269,800.

This invention relates to electrical safety devices and has for its object the provision of a fuse block and lightning arrester in which the construction is such that in the event of blowing of a fuse a new one will be automatically brought into place across the line terminals.

An important object is the provision of a device of this character embodying a movable plural fuse carrier so arranged that when a fuse blows out the carrier will drop down and bring another into place, automatically reclosing the temporarily interrupted circuit, an advantage being that in case of lightning or unusual heavy charges from any cause protection will be afforded to the circuits which may be fed from the line, and damage thereby avoided.

An additional object is the provision of a device of this character which will be comparatively simple and inexpensive to manufacture, easy to install and set, positive in action, efficient and durable in service, and a general improvement in the art.

With the above and other objects and advantages in view, the invention may consist in the details of construction and the arrangement of parts to be hereinafter more fully described and claimed, and illustrated in the accompanying drawing in which:

Figure 1 is a front elevation of my device, the lowermost fuse thereon being shown as blown out,

Figure 2 is a vertical section on the line 2-2 of Figure 1,

Figure 3 is a horizontal cross section on the line 3-3 of Figure 1,

Figure 4 is an elevation of the ground terminal carrying block,

Figure 5 is an end elevation of the structure shown in Figure 4;

Figure 6 is a detail perspective view of one of the movable arm carrying blocks,

Figure 7 is a detail perspective view of the block for carrying the ground terminal,

Figure 8 is a detail perspective view of one of the fuse holding arms.

Referring more particularly to the drawing the numeral 10 designates a support which might be a wall, slab, panel or the like, of any desired size and material. Secured upon this support in vertically spaced relation are upper and lower brackets 11 to which are secured spaced parallel vertically extending guides 12.

Secured upon the support 10 intermediate the brackets 11 is a block 13 of suitable insulating material formed in its front face with a recess 14 within which is mounted a metallic block 15, held in place as for instance by means of a screw 16 and provided with a stem 17 projecting below the lower end of the block and carrying binding means 18 for connection of a ground wire 19 therewith. Disposed against the face of the metallic block 15 is a mica plate 20 which projects beyond the forward surface of the block 13 and which may be held in place upon the block 15 by means of lugs 21 projecting from the front face of the latter and engaging through holes 22 in the former. This plate is perforated 70 at 22a.

Projecting from the front face of the block 13 are horizontal contact stops 23 and 24 held in place as for instance by means of suitable bolts 25 secured in the block 13. These members are adapted to be interposed in one of the line wires 26 and are necessarily of metal so as to serve not only as stops but also as contacts.

The numeral 27 designates a slidable carriage formed as a block of suitable insulating material and provided with channels 28 slidably receiving or engaging upon the guides 12. This carriage is normally urged downwardly by a coil spring 29 having one end seated within a recess 30 in the carriage and having its other end engaged upon a lug 31 or the like depending from the upper bracket 11.

The rear side of the carriage block 27 is formed with a plurality of recesses 32 within which are seated metallic blocks 33 arranged in vertical alinement in such position that they will successively engage against the mica plate 22 of the ground terminal structure when the carriage moves downwardly. On the front surface of the carriage block 27 are L-shaped arms 34 carried by or held in place by bolts or screws 35 which constitute their pivots and which are threaded into the respective metallic blocks 33 so that the arms will be in electrical connection with these blocks.

Located on the front surface of the carriage block at the opposite side thereof are similar L-shaped arms 36 which also act as contacts and which are pivoted by bolts or screws 37 corresponding to those indicated at 35. The

short or vertical arms of the horizontally opposite L-shaped arms 34 and 36 are adapted to have connected therewith the end portions of fuse wires 38 which are normally taut and which will, under ordinary circumstances, operate to maintain the L-shaped members in such position that the longer arms thereof will extend horizontally.

Assuming that the device has been constructed as shown and described and that fuse wires connect the various pairs of L-shaped members, it will be apparent that the spring 29 will operate to force the carriage block 27 downwardly with the horizontal arms of the lowermost L-shaped members 34 and 36 engaging upon the contacts 23 and 24 respectively. The lowermost fuse wire 38 is thus held taut and the circuit through the line is complete. Owing to the engagement of the lowermost block 33 with the perforated mica plate 20 of the ground terminal structure, it will be seen that in case of lightning or an unusually heavy discharge of any kind which would tax the carrying capacity of the line and any apparatus fed therefrom, the lowermost fuse 38 will be blown as indicated in Figure 1, while at the same time the charge will jump through the perforations 22^a and be grounded. When this fuse wire breaks the tension of the spring 29 will force the carriage block 27 downwardly until the horizontal arms of the next successive pair of L-shaped members engage the contacts 23 and 24 and consequently reclose the circuit, a fresh and clean block 33 then engaging the mica plate. This action is automatic and will be continued every time there is an electric discharge until all the fuse wires 38 have been destroyed subsequent to which a new set of fuses must necessarily be installed to restore the device to its initial condition.

From the foregoing description and a study of the drawing it will be apparent that I have thus provided a very simple device for the purpose specified which will be a great saver of annoyance and time inasmuch as it will obviate the necessity for frequent manual replacement of blown fuses. Furthermore the device will be a great safeguard in preventing injury to electric machinery and apparatus in case of static discharges and the like.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

1. In a device of the character described, a relatively stationary member of insulating material carrying a grounded contact, a perforated insulating plate covering said contact, a movable carriage of insulating material carrying a series of spaced contacts adapted to successively engage said insulating plate, means urging said carriage in one direction, contact means carried by the relatively stationary member, a plurality of pairs of pivoted arms on the carriage successively engageable with said third named contact means, and fuse wires connecting and normally held taut by said pivoted arms.

2. In a device of the character described, a relatively stationary member of insulating material carrying a grounded contact, a perforated insulating plate covering said contact, a movable carriage of insulating material carrying a series of spaced contacts adapted to successively engage said insulating plate, means urging said carriage in one direction, contact members carried by the relatively stationary member and interposed in one wire of the line, a plurality of pairs of pivoted arms on the carriage successively engageable with said contact members, and fuse wires connecting and normally held taut by said pivoted arms, said arms being of angular formation and including outwardly extending portions adapted to engage the contact members whereby upon blowing of a fuse wire the next successive arms will come into place and interpose the next successive spaced contacts between the line and the ground.

3. In a device of the character described, a relatively stationary member of insulating material carrying a grounded contact, a perforated insulating plate covering said contact, a movable carriage of insulating material carrying a series of spaced contacts adapted to successively engage said insulating plate, means urging said carriage in one direction, contact members carried by the relatively stationary member, a plurality of pairs of pivoted arms on the carriage successively engageable with said third named contacts, fuse wires connecting and normally held taut by said pivoted arms, upper and lower supporting brackets above and below said relatively stationary member, and spaced guides carried by the brackets and slidably engaged by the carriage, said insulating plate permitting static discharges to be grounded.

In testimony whereof I affix my signature.

HERBERT A. TAYLOR.
